(57) **CLAIM**

The ornamental design for a flexible towel connector, as
shown and described.

DESCRIPTION

FIG. 1 is a side perspective view of the flexible towel connector showing my new design, the side opposite being a mirror image of that shown;

FIG. 2 is a front elevational view thereof;

FIG. 3 is a top plan view thereof; and,

FIG. 4 is a bottom plan view thereof.

The broken-line disclosure of a towel is shown for illustrative
purposes only and forms no part of the claimed design.
